UNITED STATES PATENT OFFICE.

RUBY LEFI, OF NEW YORK, N. Y.

DESIGN FOR A STOCKING.

Application filed January 4, 1929. Serial No. 29,500. Term of patent 14 years.

To all whom it may concern:

Be it known that I, RUBY LEFI, a citizen of the United States, and a resident of the city of New York, in the county of New York and State of New York, have invented the new, original, and ornamental Design for Stocking, of which the following is a specification.

Reference is had to the accompanying drawing, forming part thereof, wherein

I claim:

The ornamental design for a stocking substantially as shown.

Signed at New York, in the county of New York and State of New York, this 2nd day of January A. D. 1929.

RUBY LEFI.
